8 Claims. (Cl. 260—457)

The present invention relates to capillary active compounds and to a process of preparing them.

We have found that agents of high capillary action are obtainable by introducing hydrophilic groups, directly or indirectly, into an amine of the following general formula

wherein R and R₁ stand for aliphatic hydrocarbon radicals, each containing at least 3 carbon atoms and R and R₁ together containing at least 11 carbon atoms, and R₂ represents hydrogen or an organic radical.

There may be used amines containing two radicals of high molecular weight and corresponding to the above-defined formula

Such amines are, for instance, di-(n-hexyl)-amine, diisohexylamine, di-alpha-ethylhexylamine, di-octylamine, butyldodecylamine, di-dodecylamine, di-octadecylamine, methyl-dihexylamine, diisooctyl-hydroxyethyl-amine, diheptyl-benzylamine. Such secondary amines may be obtained by known methods from carboxylic acids or mixtures of carboxylic acids, for instance, by transforming these acids into the nitriles and hydrogenating the nitriles thus obtained. Primary amines which are simultaneously formed are separated by distillation. Suitable carboxylic acids are, for instance, caproic acid, caprylic acid, capric acid, lauric acid, palmitic acid, stearic acid, oleic acid, ricinolic acid, alpha-ethylhexylic acid. The amines may be used as such or in admixture with one another. The parent materials may also be prepared from commercial mixtures of carboxylic acids. It is, for instance, possible to transform into amines, by way of nitriles, the carboxylic acid mixtures formed in the oxidation of paraffin or of mineral oils. There are further suitable the mixtures of carboxylic acids which are obtained by treating with alkali the alcohols of high molecular weight formed in the catalytic hydrogenation of carbon oxides.

Parent materials suitable for the preparation of amines are also carboxylic acids or mixtures of carboxylic acids which are obtained by treating carbon monoxide or carbon dioxide, in the presence of an olefine and perhaps of hydrogen, with steam or by causing a halogenated hydro-

carbon to react with potassium cyanide and saponifying the product obtained.

The amines may also be obtained by other known methods, for instance, by causing suitable halogenated hydrocarbons to react with ammonia or amines.

The method of rendering the products water-soluble consists in transforming the amines, by means of phosgene, into carbamic acid chlorides and then condensing these products with amino-acids, such as sarcosine, methyl-taurine, with albumin decomposition products or with amino-poly-hydroxy-compounds such as methylglucamine or hydroxy-sulfonic acids, such as hydroxyethane-sulfonic acid.

The products obtained by the process of the invention have capillary active properties and may be used for treating materials of various kind, such as textiles, leather, paper and the like.

20 They display a high wetting and emulsifying action; they may also be used with advantage as levelling and penetrative dyeing agents. Some of the products have a washing power or may be used as softening agents. The wetting effect, even in mercerizing liquors, is especially high with compounds in which the radicals R and R₁ contain branched chains. The products may be used as such, in admixture with one another or with other capillary active substances, such as 25 soap and other textile adjuvants, with colloidal substances such as mucilage, glue, water-soluble cellulose derivatives, starch, bentonite, saponine or the like or with organic solvents, such as butanol, xylenglycol; but also with inorganic salts, such as Glauber's salt, sodium carbonate, sodium pyrophosphate, trisodium phosphate, sodium metaphosphate or with agents yielding oxygen such as sodium perborate or sodium hyposchlorite.

30 40 The following examples serve to illustrate the invention, but they are not intended to limit it thereto; the parts are by weight:

(1) 213 parts of diisooctylamine are dissolved in 450 parts of chlorobenzene and dry hydrochloric acid gas is then introduced, while cooling, until saturation. The temperature is then raised to 135° C. to 140° C. and phosgene is introduced, hydrochloric acid gas being developed. When the development of hydrochloric acid gas has ceased, phosgene and hydrochloric acid gas still present are removed by the introduction of dry air and the solvent is then distilled under reduced pressure. 240 parts of diisooctylcarbamic acid chloride boiling under a pressure of 2 mm. 45 50 55 at 140° C. to 142° C. are obtained.

55 parts of diisoheptylcarbamic acid chloride of the formula

and caustic soda solution are added in the course of about 10 hours at 75° C. to 80° C., while stirring, to 330 parts of a methyl taurine solution of 10 per cent strength so that the reaction of the solution is distinctly alkaline towards phenolphthalein. The reaction product dissolves in water to a clear solution and has the following constitution:

Instead of methyltaurine there may also be used taurine.

(2) Di-(alpha-ethylhexyl)-amine is transformed by means of phosgene into the carbamic acid chloride having the formula

and 30 parts thereof are added, drop by drop, at 75° C. to 85° C. into an aqueous solution containing 23 parts of sodium n-butyltaurine in the course of 10 to 15 hours, the reaction being always alkaline towards phenolphthalein. The solution is then rendered feebly alkaline to litmus paper. The reaction product has the following constitution:

Instead of n-butyltaurine there may also be used another taurine, for instance, isobutyltaurine, alpha-ethylhexyltaurine or another aminosulfonic acid, for instance, sulfanilic acid or metanilic acid or ethanol amine sulfuric acid ester.

(3) 33 parts of n-butyl-tetradecyl-carbamic acid chloride having the formula

prepared from n-butyl-tetradecylamine and phosgene are run into a solution of 13 parts of sodium sarcosine in 30 parts of water at 70° C. to 80° C., while well stirring, the reaction being always alkaline towards phenolphthalein and the whole is stirred until a test portion dissolves in dilute caustic soda solution to a clear solution. The reaction product has the following constitution:

and may be used as washing agent.

(4) A mixture of carboxylic acids obtained by the oxidation of paraffin and containing carboxylic acids with 7 to 9 carbon atoms, is transformed by way of the nitriles and hydrogenation of these nitriles into a mixture of secondary amines, and then transformed into a mixture of carbamic acid chlorides by treatment with phosgene as described in Example 1. 30 parts of this

carbamic acid chloride are run drop by drop in the course of 7 to 8 hours at 75° C. to 80° C., while well stirring, into a solution of 22 parts of metanilic acid in 40 parts of water to which there has been added a solution of 5.6 parts of caustic potash in 10 parts of water, the reaction being always alkaline towards phenolphthalein and the whole is stirred until the product dissolves in water to a clear solution. The condensation is performed after the following scheme:

15 20 R being aliphatic radicals having from 7 to 9 carbon atoms.

We claim:

1. The process of preparing capillary active compounds which comprises causing compounds of the general formula

30 35 wherein R and R₁ stand for aliphatic hydrocarbon radicals containing at least 3 carbon atoms and R and R₁ together containing at least 11 carbon atoms, to react with phosgene and subsequently causing the condensation products to react with a member of the group consisting of aliphatic and aromatic amino compounds substituted by a radical of the group consisting of SO₃H, OSO₃H and COOH.

2. The process of preparing capillary active 40 compounds which comprises causing compounds of the general formula

45 50 wherein R and R₁ stand for aliphatic hydrocarbon radicals containing at least 3 carbon atoms and R and R₁ together containing at least 11 carbon atoms, to react with phosgene and subsequently causing the condensation products to react with an aliphatic amino sulfonic acid.

3. The process of preparing capillary active compounds which comprises causing compounds of the general formula

55 60 wherein R and R₁ stand for aliphatic hydrocarbon radicals containing at least 3 carbon atoms and R and R₁ together containing at least 11 carbon atoms, to react with phosgene and subsequently causing the condensation products to react with an aliphatic amino sulfuric acid ester.

4. The process of preparing capillary active 65 compounds which comprises causing compounds of the general formula

70 wherein R and R₁ stand for aliphatic hydrocarbon radicals containing at least 3 carbon atoms and R and R₁ together containing at least 11 carbon atoms, to react with phosgene and subsequently causing the condensation product to react with an aliphatic amino carboxylic acid.

2,251,892

5. As new compounds having capillary active properties the products of the general formula:

5

wherein R and R₁ stand for aliphatic hydrocarbon radicals containing at least 3 carbon atoms and R and R₁ together containing at least 11 carbon atoms, R₂ stands for a member of the group consisting of aliphatic and aromatic hydrocarbon radicals, R₃ means a member of the group consisting of hydrogen and aliphatic hydrocarbon radicals and Y stands for a member of the group consisting of SO₃H, OSO₃H and COOH.

10

6. Compounds as defined in claim 5, wherein Y stands for COOH.

7. As a new capillary active compound

8. As a new capillary active compound
